G. W. BROOKS

METALLIC NONSKID TREAD

Filed July 18, 1925

FIG. 1

FIG. 2.

FIG. 3.

INVENTOR.

BY *GEORGE W. BROOKS*

W. G. Charles
ATTORNEY.

UNITED STATES PATENT OFFICE.

GEORGE W. BROOKS, OF TOPEKA, KANSAS.

METALLIC NONSKID TREAD.

Application filed July 18, 1925. Serial No. 44,527.

My invention relates to a metallic nonskid tread, being made of brass, steel or other like metals.

The object of my invention is to provide a tread to be placed as a panel through door ways, or other points where travel is con- 50
gested.

A further object of my invention is to provide a tread having a series of dove-tail 10
grooves, the edges of which will grip a flex-
ible body impinged thereon.

A still further object of my invention is to provide a tread having a series of grooves in close proximity to each other and the side 15
walls thereof converging upward, for a spe-
cific purpose hereinafter described.

A still further object of my invention is to provide a border around ornamental panels in concrete, having the nonskid feature 20
in its exposed surface, and the portion ex-
tending downward functioning as a bond
between the adjacent panels.

Referring to the drawings, like characters will refer to like parts in the different views. 25
Figures 1, 2 and 3 are modified forms for borders dividing tile and concrete, the same being reversible, that is to say, the double dove-tail may be placed upward, and the single dove-tail placed downward in the 30
concrete, the said dove-tailed members being connected by a webbing of varying forms, the said webbing functioning as vertical anchoring means for the dove-tailed plate, and transverse bonding means for the con- 35
crete; that is to say, the contraction of the concrete will tend to separate along the lines of the webbing, the tension being in opposite directions on the extension members as at A and A' in Fig. 1, while in Fig. 2 the 40
tension of separation will be imposed on the extensions at B and in the dove-tail at B'.

I now wish to call attention to the value of the small amount of wearing away of the plate which is means of the up-keep of the 45
nonskid feature, that is to say the wear that

would take place on the exposed face of the tongue 7 tends to sharpen the edges 6 of said tongue which would preserve the grip that it would not have otherwise, and by reason of the beveled sides, the edges are 50
more easily sharpened, therefore the nonskid feature remains the same until the tongues have been worn to the level of the base of the grooves, as at F.

I am aware that nonskid plates have been 55
made where curvatures have been employed and also grooves that have been filled with other materials, and grooves that are rectangular in the section, but such I do not claim as my invention, such modifications 60
may be made as to the size of the dove-tail grooves and the slant of the side walls there-
of, and other modifications functioning as nosing protection.

Having thus described my invention, what 65
I claim as new and desire to secure by Letters Patent is:—

1. In a metallic nonskid tread, strips of the tread having dove-tail grooves in the 70
face thereof, a connecting member for said strips, said member joining with the back of said strips, and integral therewith and functioning as bonding and anchoring means substantially as shown and for the purpose described. 75

2. In a metallic nonskid tread, a member having two grooved treads of different widths paralleling each other and reversible, a webbing having irregular sides connecting said treads and integral therewith, all as, 80
and for the purpose described.

3. In a metallic nonskid tread, a metal structure having a dove-tailed grooved member on each side thereof of different widths, the said members being parallel and connected by a webbing, extension members on the webbing as bonding means in the concrete, all as, and for the purpose described. 85

GEORGE W. BROOKS.
